UNITED STATES PATENT OFFICE.

EDWARD A. BANSCHBACH, OF CHICAGO, ILLINOIS.

RECORD-HOLDER.

1,370,399.

Specification of Letters Patent.

Patented Mar. 1, 1921.

Application filed May 11, 1918. Serial No. 233,937.

To all whom it may concern:

Be it known that I, EDWARD A. BANSCHBACH, a citizen of the United States, residing at Chicago, in the county of Cook and 5 State of Illinois, have invented certain new and useful Improvements in Record-Holders, of which the following is a specification.

This invention relates particularly to a 10 holder for flat disk talking machine records, although of course it may have a more general application as a filing case, or any similar use.

The object of the invention is to provide 15 a holder which may be easily and quickly handled and opened, and embraces a construction which occupies a minimum of space when in the open position, but at the same time clearly discloses indexed designating spacers so that any desired record 20 may be quickly taken from the holder without disturbing or removing any of the other records.

A further object of the invention is to insure 25 that the holder will be properly opened, and to prevent it from being opened too far.

The invention consists in the novel construction, combination and arrangement of 30 the parts.

In the accompanying drawings—

Figure 1 is a perspective of a record holder constructed in accordance with the principles of this invention.

35 Fig. 2 is a view of the back of the record holder showing the index and its cover.

Fig. 3 is a view of one of the container parts of the holder.

40 Fig. 4 is a sectional view of the holder.

Fig. 5 illustrates a modification of the hinged supporting means attached to the holder.

It is customary to use an album for holding 45 disk records for phonographs which requires a considerable surface for opening the album so that the desired records may be taken from the pockets thereof. In this type of container it is necessary to turn over each leaf or pocket in order to find the desired record. In the present invention the 50 sides of the holder do not lie flat upon the supporting surface, but are held upward in angular position so that a considerably less space is taken up by the holder in its open 55 position than if the covers were laid flat upon the surface. The opening of the cov-

ers places the supports in their proper position, and the indexed edges of the partitions between the records clearly indicate the position not only of one, but all of the 60 records in the holder at the same time, so that any one of the records may be removed in the least time and with the least trouble without idly searching and turning over the leaves to find it.

65 In the preferred form of this holder there is a rigid back 1, to which covers 2 are hinged along one side thereof, the other three adjacent edges of each cover 2 having overlapping portions 3 at the corners which 70 are secured together by fastening devices 4. One of these covers is slightly larger than the other so that when they are pressed together it fits over the other cover, and the edges are of substantially the same width 75 as the back 1 so that in closed position the holder has a double thickness of the material inclosing the cover. A snap fastening 5 is commonly provided at the edges of the covers 2 to hold them together in their 80 closed position.

The outer edge of the back, as shown in 85 Fig. 2, provides a considerable space for an index 6 of the contents of the holder, and a cover 7 of some transparent material, such as celluloid, may be provided for the back so that an index strip may be slipped between it and the back 1, which is clearly visible through the transparent material 7.

Within the covers 2 are a plurality of 90 thin partitions 8 which are graduated in at least one dimension to form an index 9 for all the partitions, which is clearly visible. The corners of these partitions 8 may also be cut off to form an index 10 for 95 distinguishing the partitions in a different manner, and one edge of these partitions 8 may be variously notched to form a separate index 11 at a different angle from the other index 9, which may be used for indexing the records in a different manner. For example, the index 9 may be used to designate the name of the selection, as the name of a song; the index 10 may be used to indicate the character of the selection, as a 100 two-step or march; and the index 11 may be used to indicate the name of the author or producer of the selection.

Hinged on the outsides of the covers 2 are supports 12 which open outwardly from 110 the back 1 and may be provided with a snap fastening 13 for holding them against the

- 2
- covers. In order to limit the outward hinged movement of the supports 12, a flexible cord or tape 14 is attached to the inside of each support and extends through an opening 15 of the cover and through holes 16 in the partitions 8 within the holder. When the supports 12 are folded against the covers, the tapes 14 simply fold up between the support and the cover and lie loosely within the covers 2, it being understood of course that the tape 14 extends from one support through the covers to the other support. Near the back 1 of the holder, the covers are also provided with perforations 17, and the partition members 8 are likewise provided with perforations 18 through which a cord or tape 19 is inserted, there being some slack in the tape so that it will permit the opening of the holder. These tapes 14 and 19 are preferably arranged on the arc of a circle, as shown more clearly in Fig. 3, so that they may form a partial support for any record that may be contained in the holder.
- In order to insure that the supports 12 will be moved to their proper position, as shown in Fig. 1, a flexible band 20 is attached to the outer side of each support 12 and extends through openings 21 in the covers 2 and through corresponding openings 22 in the partitions 8. As the ends are attached to the opposite supports 12, the opening movement of the covers 2 will throw the supports outwardly, there being sufficient slack in the band 20 to insure the operation of the supports 12 when the covers 2 are sufficiently opened. It will be seen, therefore, that the tape 14 limits the outward movement of the supports 12, and the band 20 insures that they are moved into their supporting position.

Instead of having the tapes 14 attached to the supports 12, a double hinged construction, as shown in Fig. 5, may be employed. In this construction two members 23 are flexibly hinged to each other and to the outer edge of one of the supports 12 and the back 1 of the holder, respectively. The outward movement of the support is limited by these members 23, and when the supports are folded inwardly, the members 23 collapse between the support and the cover to which they are attached.

In order to strengthen the back 1 and to hold the bent edges of the covers 2 in proper position at the ends of the back 1, a stiff plate 26 is attached to the back which is formed with turned up ends 27 adapted to be placed outside of the overlapping free edges 28 of the covers 2, as shown in Fig. 1. When the holder is supported or carried in any other than the open position, the weight of the records within the holder may be so great as to cause these overlapping edges 28 to be bent or deflected, but the bent ends 27

of the plate hold the overlapping sides 28 in position regardless of the position of the holder and of the weight of the records within it.

It is obvious that the operation of this holder is so simple that no further explanation is necessary, and it will furthermore be evident that as soon as the holder is opened, each and every record is immediately and easily accessible, and its place can be ascertained.

I claim:

1. In a record holder, a back and covers hinged thereto, a support hinged on the outside of each cover adapted to swing outwardly for engaging a plane surface upon which the back rests to hold the covers angularly apart in a partially opened position, and means depending upon the movement apart of the covers for swinging the supports outwardly in a supporting position. 85
2. In a record holder, a back and two covers hinged thereto and foldable one within the other, a support hinged on the outside of each cover adapted to swing outwardly for engaging a plane surface upon which the back rests to hold the covers angularly apart in a partially opened position, means operated by the angular movement of the covers to swing the supports outwardly, and a connection between the supports and the covers to limit the outward swinging movement of the supports. 90
3. In a record holder, a back and two covers hinged thereto and foldable one within the other, a support hinged on the outside of each cover adapted to hold the covers upright in a partially opened position, and a flexible band extending through the covers and attached to the outsides of the supports to swing them outwardly when the covers are swung apart into a partially opened position. 100
4. In a record holder, a back and a pair of covers hinged thereto foldable one within the other, means for supporting the holder on its back with the covers in a partially opened position, and a plurality of graduated index partitions within the covers made accessible and all the indices visible when the covers are in a partially opened position. 110
5. In a record holder, a back, covers hinged thereto and foldable one within the other, means for supporting the holder upon its back with the covers in a partially opened position, and graduated index partitions having index notches at one side and corners removed at the other side forming indices visible when it is supported in the 115 partially opened position. 120
6. In a record holder, a plurality of index partitions having corresponding corners removed to form a graduated index, circularly arranged means for supporting disk- 130

shaped objects between said partitions so that said partitions are spaced apart thereby, and means for supporting said partitions in a partially open position so that they extend 5 in planes at oblique angles to the support on which said holder rests.

7. In a record holder, a back and covers hinged thereto foldable one within the other, means for supporting the holder on its back 10 in a partially opened position, a plurality of partition sheets within the holder, and flexible members extending through the partition sheets and through the covers at the edges thereof for limiting the angular opening 15 of the covers and for forming a retainer at the ends of the holder for records contained therein.

8. A holder for circular disk records comprising a back and covers hinged thereto foldable one within the other, supports hinged to the covers for holding them angularly apart with the holder supported on its back, means for limiting the outward movement of the supports, a plurality of 25 indexed partition sheets within the holder, means for automatically opening the supports when the covers are opened, said means comprising flexible bands which extend through the edges of the partition 30 sheets and through the covers for partially confining the records between the partition sheets, and fastening devices for holding the supports against the covers and the covers together when the holder is closed.

35 9. A record holder comprising a back and covers hinged thereto at each side of the back, each cover having one or more edges turned inwardly and the covers foldable one within the other, and a rigid support secured to the back and bent inwardly at the 40

ends of the back over the covers to form a support for holding the edges of the cover in place.

10. A record holder comprising a back and covers hinged thereto at opposite sides 45 of the back, each cover having its edges turned inwardly and the covers foldable one within the other so that the edges thereof overlap adjacent the ends of the back, and a supporting plate secured to the back and 50 extending over the outsides of the overlapping cover edges forming a support to prevent the edges from bulging outwardly.

11. A record holder comprising a back and covers hinged thereto at each side of the 55 back, each cover having its three outer edges turned inwardly and secured together at the corners and one cover foldable within the other so that the edges thereof will overlap, and means attached to the back for 60 supporting the overlapping edges adjacent the ends of the back to prevent these edges from bulging due to the weight of the records within the holder when the holder is in any other than open position. 65

12. In a record holder, a plurality of index partitions graded in size to expose a portion of the edge of each partition for indexing said partitions, circularly arranged means for holding circular records 70 of varying sizes between said partitions, said partitions having the corners thereof removed to provide exposed portions for a supplemental index, and means for holding said index partitions in partially open position to expose the indices thereon to view. 75

In testimony whereof I have signed my name to this specification on this 6th day of May, A. D. 1918.

EDWARD A. BANSCHBACH.
